CALIFORNIA

BRAKE CONSTRUCTION

Application filed July 12, 1929. Serial No. 377,679½.

This invention relates to a brake construction and relates particularly to a brake construction applicable to the drum of a well drilling rig, or the like.

5 The draw works of a well drilling rig usually embodies a winding drum upon which the cable used in handling drilling tools, well casing, etc., is wound. In the usual arrangement the drum is operated in one direction by a power drive and in the other direction by the weight of the parts carried by the cable. The rotation of the winding drum is controlled by one or more manually controlled brakes. The common type of 10 brake consists of a flexible band operable to engage a flange or rim on the drum. The band is usually provided with a suitable friction lining. The common forms of winding drum brakes give considerable trouble, one 15 reason being that the lining becomes smooth and slippery and fails to effectively engage or grip the brake flange.

It is a general object of the invention to provide a dependable, effective brake for the 20 winding drum of a well drilling rig.

It is another object of the invention to provide a brake construction that can be readily applied to the forms of winding drums in general use.

25 Another object of the invention is to provide a brake construction for the winding drum of a well drilling rig that embodies an interrupted braking surface.

It is another object of the invention to provide a brake construction for the winding drum of a well drilling rig that embodies a plurality of like units in the form of shoes attached to a flexible band, each unit carrying 30 lining to engage the braking flange of the drum.

It is a further object of the invention to provide a brake construction of the character mentioned in which the shoes are individually replaceable.

35 It is another object of the invention to provide an improved braking rim or flange in a brake construction of the character mentioned.

A further object of the invention is to provide a simple, practical, and inexpensive

brake construction for the winding drum of a well drilling outfit.

The various objects and features of our invention will be best and more fully understood from the following detailed description of a typical, preferred form and application of the invention, throughout which description reference is had to the accompanying drawing, in which:

Fig. 1 is a front elevation of a portion of the draw works of a typical well drilling rig. Fig. 2 is an end view of the draw works showing the brake construction provided by this invention embodied in the winding drum. Fig. 3 is an enlarged vertical detailed sectional view taken as indicated by line 3—3 on Fig. 1. Fig. 4 is a vertical transverse detailed sectional view taken as indicated by line 4—4 on Fig. 3. Fig. 5 is a vertical longitudinal detailed sectional view of one of the 60 shoes or units, being a view taken substantially as indicated by line 5—5 on Fig. 4. Fig. 6 is a vertical detailed sectional view of one of the shoes, being a view taken as indicated by line 6—6 on Fig. 5. Fig. 7 is a vertical detailed sectional view of another form of the 65 invention.

The brake construction provided by this invention is particularly adapted to be used in connection with the winding drum of the 70 draw works of a well drilling rig. The invention, however, is suited for use in connection with various devices and is not to be considered as limited to the particular form and application about to be described, but is to be 75 understood as including any features that may fall within the scope of the claims.

In the accompanying drawing we have illustrated the brake construction provided by this invention applied to the winding drum 90 of a typical well drilling rig. The portion of the well rig illustrated in the drawing includes, generally, a frame 10, a line shaft 11, a drum shaft 12 mounted on the frame in suitable bearings 13, a winding drum 14 rotatably mounted on the shaft 12, and a clutch 15 for connecting the shaft 12 and drum 14 for rotation. The end 16 on the drum is provided with the improved braking rim or flange 17, and a brake band 18 surrounding 95 100

the flange 17 and carrying a plurality of the shoes 19. The shoes 19 provided by this invention are detachably mounted on the inner side of the band 18. A handle or lever 20 is connected with the band 18 for operating the band to bring the shoes 19 into engagement with the flange 17. It is to be understood that the flanges 17 may be provided at both ends of the drum and the bands surrounding the flanges may be connected with a single operating lever.

The brake construction provided by this invention includes, generally, the braking rim or flange 17 carried by the end 16 of the winding drum 14, the flexible band 18 surrounding the flange 17, and the spaced shoes 19 detachably connected to the band 18 and adapted to be brought into engagement with the flange 17.

20 The braking flange 17 is an annular member adapted to be applied to or formed on the periphery of the end 16 of the drum 14. In the construction illustrated an annular recess 21 is provided in the peripheral portion of the outer side of the end 16. The recess 21 extends radially inward from the periphery of the end 16 forming a shoulder 22. The flange 17 is preferably arranged so that it extends axially outward from the end 16 and is 25 immediately beyond the periphery of the end 16. The inner side of the flange 17 is provided with an inwardly extending radial flange 23 adapted to fit into the recess 21. The flange 17 may be attached to the end 16 30 by bolts 24, or the like, extending through the radial flange 23 and the end 16. The outer or peripheral side of the braking flange 17 is provided with an indentation in the form of a V-shaped groove 25. The groove 25 extends completely around the peripheral face of the flange 17. The groove presents two angularly disposed flat walls or faces 26. The faces 26 extend outwardly from the center of the groove 25 to the edges of the 35 flange 17.

The band 18 is a flexible member surrounding the flange 17. The band 18 may be similar to the brake bands in general use. It is sufficiently wide to completely cover the 40 groove 25 and has one end connected to a stationary part of the well derrick by means of anchor members 28, or the like, and has the other end connected to the operating lever 20. The two ends of the band 18 are preferably 45 relatively near one another so that the band extends a substantial distance around the flange 17. The band is normally spaced from the periphery of the flange 17 and is operable by the lever 20 to move the shoes 19 into engagement with the faces 26 of the groove.

The shoes 19 are mounted on the inner side of the band 18. The shoes 19 are spaced circumferentially on the band and are preferably alike in formation. Each shoe includes

a metal carrier or frame 30 and friction lining. The lining may be in two sections 31. The frame 30 has two like body parts 33 angularly related to correspond to the configuration of the groove 25 in the flange 17. 70 The parts 33 are joined or connected at the center of the shoe and extend to the edges of the band 18. The parts 33 may extend any desired distance circumferentially along the inner side of the band. End flanges 34 are 75 provided on the frame 30 and extend inwardly from the end edges of the parts 33. The outer edges of the end flanges 34 are preferably made parallel to the surfaces of the parts 33. The ends 34 lend rigidity to the construction and close the opposite ends of the shoe. Side flanges 35 extend along the outer edges of the parts 33 between the ends 34. The shoe may be detachably mounted on the band 18 by suitable means, say, by bolts 38 80 extending through the band and through mounting flanges 39 at the ends of the shoe. The mounting flanges 39 continue inwardly from the end flanges 34 and have turned parts or feet fitting against the band and receiving bolts 38 which connect the shoe to the inner side of the band 18.

The sections 31 of the friction lining may be formed of any suitable material. A section 31 is arranged on each part 33 of the shoe. The sections are preferably flat and are arranged on the parts 33 to engage the faces 26 of the groove 25 when the lever is operated to tighten the band on the flange 17. The sections 31 preferably completely cover 100 the inner sides of the parts 33, extending between the flanges 34 and from the side flanges 35 to the center of the base. Bolts or other suitable means 37 may extend through the parts 33 to attach the sections 31 to the shoe. 105 The bolts 37 may be countersunk in the lining sections 31 as illustrated in the drawing. The end flanges 34 and the side flanges 35 assist in maintaining the lining sections in their proper positions on the parts 33. The sections 31 project beyond the flanges 34 and 35 so that only the lining sections engage the flange 17 when the lever 20 is actuated. It will be obvious that each shoe 19 may be provided with a unitary or continuous section of 110 friction lining without departing from the spirit of the invention.

In Fig. 7 of the drawing we have illustrated an arrangement of the invention wherein the mounting flanges 39^a of adjoining shoes 19 overlap each other. In this form of the invention each bolt 51 extends through the band 18 and through the flanges 39^a at the adjoining ends of the two adjacent shoes. 115

In operation the band 18 is arranged 120 around the flange 17 so that the lining sections 31 are normally free of the faces 26 of the flange 17. When it is desired to brake, or to stop the drum, the lever 20 is operated so that the sections 31 of the friction lining are 125 130

brought into pressure engagement with the faces 26. The shape of the groove 25 and the arrangement of the sections 31 on the shoes 19 are such that the pressure exerted through the sections 31 acts axially in the opposite directions as well as inwardly or radially. The shoes 19 are always maintained in their proper positions as the band 18 cannot shift axially on the flange 17. The sections 31 are particularly effective in gripping or engaging the flange 17 as they present an interrupted braking surface which does not become smooth and inefficient. As the sections 31 become worn, the shoes 19 may be easily removed individually and the lining replaced on the shoes, or other shoes may be replaced on the band 18. The flange 17 is adapted to be mounted on the various forms of winding drums in general use, and the shoes 19 may be mounted on the common forms of brake bands in place of the usual brake lining. It is to be noted that the brake construction provided by this invention is extremely inexpensive and is effective of operation.

Having described only a typical, preferred form of our invention, we do not wish to limit ourselves to the specific details set forth, but wish to reserve to ourselves any changes or variations that may appear to those skilled in the art or fall within the scope of the following claims.

Having described our invention, we claim:

- 35 1. A shoe to be mounted on a brake band including, a frame including convergent body parts, brake lining on the body parts, side flanges on the body parts at the edges of the lining and mounting flanges for the frame.
- 40 2. A shoe to be mounted on a brake band including, a frame, convergent parts on the frame, lining on the said parts, end flanges on the parts, side flanges on the parts, the said side and end flanges operating to retain the lining on the said parts, and mounting flanges on the frame for mounting the frame on the band.

In witness that we claim the foregoing we have hereunto subscribed our names.

50 WILLIAM ARTHUR VOCK.
